UNITED STATES PATENT OFFICE.

WILLIAM MILLINGTON, OF GRAND RAPIDS, MICHIGAN, ASSIGNOR TO THE AEOLIAN COMPANY, A CORPORATION OF CONNECTICUT.

DESIGN FOR A CABINET FOR PHONOGRAHPS.

Application filed July 15, 1921. Serial No. 485,083. Term of patent 7 years.

To all whom it may concern:

Be it known that I, WILLIAM MILLINGTON, a citizen of the United States, residing in Grand Rapids, county of Kent, and State of Michigan, have invented a new, original, and ornamental Design for a Cabinet for Phonographs, of which the following is a specification, reference being had to the accompanying drawing, forming part thereof.

The figure is a perspective view of a cabinet for phonographs showing my new design.

I claim:

The ornamental design for a cabinet for phonographs substantially as shown.

In testimony whereof I have hereunto signed this specification.

WILLIAM MILLINGTON.
